APPARATUS FOR REDUCING TUBULAR BLANKS

Frank R. Krause, Ellwood City, Pa.

Application December 2, 1936, Serial No. 113,839

16 Claims.

(Cl. 80—12)

This invention relates to a method and apparatus for reducing and elongating metal blanks, and relates more particularly to the rolling of seamless tubes.

- 5 In tube reducing and elongating by longitudinal rolling on a mandrel as now practiced, a tubular blank is reduced a relatively small amount in each of a series of independent full-length roll passes until it finally acquires the desired size.
- 10 The blank is fed into the rolls which roll it from front end to rear whereby the rolls continuously roll against the portion of the blank having the greatest diameter and the draft therefore remains uniform throughout. The reduction that can be made in any one pass is limited both by the tendency of the rolls to slip against the blank if too great a reduction is attempted, and by tearing of the metal when the reduction becomes too great.
- 15 It is among the objects of this invention to provide a method and apparatus for rolling seamless tubes from tubular blanks in which only one mill is necessary, in which there is substantially no limit to the reduction that can be made
- 20 while a blank is passing through the mill only once, in which the character of the metal of the blank is improved, and in which the life and capacity of the mill is increased.

In accordance with this invention a tubular blank mounted on a mandrel is reduced to a tube of desired dimensions by passing it only once through a mill having grooved rolls which are caused to periodically roll simultaneously toward the front end of the blank and the axis thereof, and then parallel to the axis. The movement of the rolls is brought about by relative reciprocable movement between the blank and track surfaces which the rolls engage. During the return strokes of the rolls between working strokes, unrolled increments of the blank are successively brought into position for reduction by the rolls. The tracks are preferably so formed that they cause the rolls to approach each other gradually during the first part of each working stroke, then to approach each other quite rapidly followed by another gradual approach just before the tracks cause the rolls to move parallel to the axis of the blank.

The invention is illustrated in the accompanying drawings in which Fig. 1 is a plan view, partly in section, of my tube-rolling mill; Fig. 2 is a central vertical section thereof; Fig. 3 is a view of the delivery end of the mill; Fig. 4 is a plan view, partly in section, of apparatus for feeding and turning a blank in the mill; Figs. 5 and 6 are side

and end views, respectively, of that apparatus; Fig. 7 is a view showing diagrammatically the relative positions of tracks and rolls at different points in the rolling operation; Fig. 8 is a fragmentary vertical section showing a modification of this invention; Fig. 9 is an enlarged vertical section taken on the line IX—IX of Fig. 8; and Fig. 10 is a vertical section through the rolls taken on the line X—X of Fig. 9.

Referring to Figs. 1, 2 and 3 of the drawings, a track housing 1, provided with an opening 2 extending from end to end thereof and having parallel horizontal and vertical side walls, is slidably mounted in a bed plate 3. Preferably, the housing is reciprocated in the frame by a crank arm 4 pivoted to the base of the housing and to a disc 5 rotated by a drive shaft 6. Mounted in any suitable manner, adjustably if desired, in the rear portions of the horizontal walls of opening 2 is a pair of hardened track plates 7. Another pair of track plates 8 is mounted in the vertical side walls of opening 2 midway between tracks 7. Disposed one behind the other in the housing opening are roll housings 9 and 11, the rear housing 9 having side flanges 12 slidable along the top and bottom surfaces of tracks 8, and the front housing 11 having similar flanges 13 for the same purpose.

A pair of horizontal reducing rolls 14 is journaled in bearing blocks 16 slidable in recesses in the side walls of housing 9, and a pair of vertical finishing rolls 18 is journaled in like manner in blocks 19 disposed in recesses 21 in the top and bottom walls of housing 11. The front and rear pairs of rolls are each provided centrally with annular grooves 22 and 23, respectively, the two sets of grooves forming roll passes through which a cylindrical mandrel 24 extends. The grooves in the reducing rolls are larger than those in the finishing pair because the former must engage unreduced portions of the tubular blank 26 mounted on the mandrel, while the latter engage only portions of the blank that have already been reduced by the other rolls. The side walls of the grooves in the reducing rolls are substantially flat and flare outwardly at a tangent to the unreduced portion of the blank, as shown in Fig. 1, but the grooves in the finishing rolls are semi-circular in cross section because they form the pass in which the tube is smoothed and rounded.

It is a feature of this invention that the track plates are so formed that as the track housing is moved forward during each working stroke the track plates carried by it roll the rolls forward against the stationary blank toward its front end and simultaneously cause them to approach the

axis of the mandrel, and thereby, by a combined rolling and sinking operation, reduce and elongate the blank. During the latter part of the working stroke the rolls travel parallel to the axis of the mandrel to form a reduced cylindrical tube. Accordingly, as shown in Fig. 2, tracks 7 are provided adjacent their rear ends with parallel areas 27 merging into areas 28 inclined away from each other toward the front of the track housing. Likewise, as shown in Fig. 1, tracks 8 have parallel areas 29 terminating in outwardly inclined areas 31 at their front ends.

Consequently, as the track housing starts to move forward from the position shown in Fig. 2 in which horizontal rolls 14 loosely engage an unreduced increment of the blank a portion of which has already been reduced during preceding working strokes of the mill, the inclined areas of tracks 7 move into frictional engagement with the adjoining rolls and force them tightly against the blank. Continued movement of the tracks causes these rolls to roll forward and inwardly at the same time. This reduces the previously unrolled cylindrical increment to tapered form and further reduces the blank's previously tapered portion the smaller end of which is thus reduced to an unfinished tube by the rolls when the parallel areas of the tracks reach them and move them in parallel paths. During the same working stroke vertical rolls 18 are moved forward and inwardly along the reduced unfinished portion of the blank by track plates 8 until the parallel areas of the tracks reach the rolls, whereupon they travel parallel to the axis of the tube and finish it.

It will be noted in Fig. 2 that the front end of the tube has been allowed to upset by sinking over the tapered front end of the mandrel at the start of rolling. The reason for this is to increase its wall thickness to prevent the front end from spreading and splitting open while it is being reduced. The remaining increments of the blank that are successively reduced are supported at both ends of their zone of contact with the rolls by portions of the blank not under rolling pressure and therefore do not spread out and split open.

As the track housing returns to its starting position at the conclusion of each working stroke the roll housings are retarded in their backward movement relative to bed plate 3 after the rolls have rolled back to the inclined areas of the track plates to permit them to spread apart and release the blank for an increment of feed. This retarding of the roll housings is preferably accomplished by a fluid pressure cylinder 32 mounted on the rear end of the bed plate with its piston 33 connected to rear roll housing 9. Sufficient pressure is maintained behind the piston to retard the roll housings until a stop 34, attached to the front end of the track housing, engages roll housing 11 and pushes both housings back to their starting positions, as shown in Fig. 2. At the conclusion of the return stroke the fluid under pressure is reversed to the front end of cylinder 32 to hold the roll housings stationary at the start of the working stroke until the rolls are in firm frictional engagement with the tracks and blank. The two roll housings are connected together, but it is a spring connection 36 to allow their separation for a short distance during rolling to accommodate differences in roll speed.

Although the inclined area of each rear track 7 may be flat lengthwise when relatively small reductions are being made, for making large reduc-

tions with the same length working stroke each inclined area is preferably in the form of a reverse curve with its ends nearly horizontal and its central portion more steeply inclined to the horizontal, as best shown in Fig. 7. The principal reason for this shape of track is to prevent the rolls from slipping on the track or blank. The likelihood of roll slippage is greatest when they first move into contact with the blank, and also when they approach the smaller end of the tapered portion of the blank that has already been reduced a material extent and has a thin unyielding wall. With tracks of the shape just referred to, the draft is gradually increased during the beginning and gradually decreased during the ending of the working stroke of the mill so that there will be no roll slippage at those times.

With track plates of either shape each successive draft starts at zero on the periphery of the unrolled increment and gradually increases to its maximum amount. This gradual increase of the draft with its accompanying reduction orients the crystals in the metal before subjecting them to more severe elongations, and thereby improves the character of the metal, and this improved portion of the metal is not affected adversely during the next working stroke of the mill when it is subjected to the maximum draft, but is still further improved because this maximum draft causes only gradually increasing elongation of the blank. In prior tube rolling practice in which rolls roll a blank from front to rear and continuously against the portion of the blank having the greatest diameter and wall thickness, the start of the draft at any given point along the blank is the most sudden and the crystals are therefore caused to fracture when elongated under heavy drafts.

The shape of the rear tracks and the outline of a blank rolled between them is best shown in the diagram of Fig. 7 where the relation of the different members to one another when in three different positions is also illustrated. The full lines show the shape of a portion of a blank 26 in the process of being reduced, and also the positions of the tracks 7 and rolls 14 at the start of a working stroke after the blank has first been advanced a step to subject an unrolled increment A—B to the action of the rolls. As the tracks advance to the position indicated by broken lines they roll the rolls into their broken line position wherein increment A—B and the adjoining portion of the partly reduced blank are further reduced an amount also shown by broken lines. It will be seen that at this stage the increment A—B has been reduced but slightly, the reduction increasing as the front of the increment is approached. On the other hand, the previously reduced portion near line C is reduced materially during this working stroke. As the tracks continue to advance to the dotted line position in which their parallel areas reach the rolls, also dotted, the blank is reduced to the shape indicated by both broken and dotted lines. The portion C—D of the blank is materially reduced, but as line D is approached the draft starts to diminish, and by the time the rear ends of the tracks reach the rolls another portion of tubing of substantially uniform wall thickness has been added to the preceding portion.

With this type of mill in which the rolls roll a tubular blank step by step towards its front end while they bodily approach each other, blanks can be reduced in a single pass through the mill an amount heretofore thought impossible, because the same draft can be taken in making a large

reduction that is used in making a small one. This is because the amount of reduction does not depend upon the draft which is governed by the amount of feed, but upon the shape of the tracks 5 and the length of the working strokes. The track plates can be so shaped that large reductions can be made with short working strokes, because roll slippage is prevented by the shape of the ends of the track plates, and also by the 10 fact that the apex of the contact angle F (Fig. 7) is at the junction of the rolls and tracks instead of at the axes of the rolls so that the angle is smaller for any given area of contact between the rolls and blank. Also with the hardened 15 track plates backing up the rolls, the rolls are supported on substantially flat surfaces throughout their length and the rolls can therefore be of relatively small diameter.

Another factor that differentiates this mill from 20 those known heretofore is that the metal under rolling pressure is distributed on both sides of the vertical center line of the rolls. This particular area of metal is indicated by the character E in Fig. 7. As the metal must therefore be distributed 25 on both sides of this center line it must naturally flow in opposite directions therefrom, as indicated by the arrows, whereby the metal in the pass is under tension as well as compression as it is being displaced and therefore spreads very 30 little. In fact, the spreading of the metal is very much less with this mill than in any other rolling operation in use today. As the flow of metal in this case is due to a combination of tension and compression forces, the metal pressure or separating force exerted on the rolls is less than it 35 would be if compression forces alone were relied upon to reduce the blank. An advantage flowing from this is that the mill is subjected to less strain than the ordinary mill, and its capacity and life are therefore increased.

As indicated before, while the track housing is 40 making its return stroke, i. e., returning to its starting point during each cycle, and while the rolls are released from the blank due to their backward movement being retarded by piston 45 33, the blank and mandrel are fed or advanced a step to subject the next succeeding unrolled or unreduced increment of the blank to the action of the rolls.

A desirable feeding apparatus for this purpose 50 is illustrated in Figs. 4, 5 and 6 wherein a carriage 51 is slidable on a table 52 toward and away from the mill which is not shown in these figures but which would be disposed at the right of the apparatus as viewed in Figs. 4 and 5. Journaled in 55 one side of the carriage is a hollow spindle 53 in which the rear ends of the blank and mandrel are clamped by means of a chuck 54 mounted on the front end of the spindle. The carriage is constantly biased toward the mill by a fluid pressure cylinder 56 and a piston rod 57, but its movement is obstructed by a stop 58 projecting up through a slot 59 in the table from a screw 61 on which it is threaded. This screw is shown disposed beneath one side of the table for the sake 60 of clearness, but if desired it can be located in the center of the table. The screw is constantly rotated through a belt 62 and any suitable adjustable speed drive, such as a Reeves drive 63, from a shaft 64 geared to drive shaft 6 of Fig. 1.

At periodic intervals, that is, during each working stroke of the mill, the tube and mandrel are clamped in fixed position by an automatic clamp comprising a downwardly opening fluid pressure cylinder 65 mounted in the table directly beneath

the blank and containing a piston 66 provided at its lower end with a cross-head 67 which is connected by tie rods 68 to a clamping bar 69 above the blank. The cylinder should be disposed as close to the mill as possible, and may even be mounted in a separate support between the table and mill. When fluid pressure is introduced into the upper end of this cylinder the piston is forced downwardly, which draws the clamping bar down against the blank and clamps it against the upper 10 end of the cylinder. Fluid pressure is automatically supplied to the cylinder and released therefrom by any well-known automatic control which may be actuated by the reciprocating track housing 15.

While the blank is thus clamped in position and an increment of it is being elongated in the mill, stop 58 continues to move forward on screw 61 whose speed and pitch determine the amount the stop can move during the interval that the 20 blank is held by the clamp. At the moment the blank is released, which is during the return stroke of the mill when the rolls are free of the blank, cylinder 56 connected to the carriage forces the carriage ahead until it strikes stop 58, whereupon 25 the clamp again grips the blank and holds it stationary for the next reducing and elongating step. Consequently, the stop determines the amount the blank is fed forward each time, and this feed is variable by the Reeves drive.

To rotate the mandrel any desired number of 30 degrees while it is being fed forward, so that the blank will be properly rolled on all sides, a pinion 71 having an axial passage therethrough is journaled in the carriage where it meshes with a gear 72 keyed on the carriage spindle. The passage through the pinion is preferably square for receiving a square shaft 73 to produce a splined connection that permits the carriage to move forward on the square shaft without interfering with rotation of the pinion. To turn shaft 73 a predetermined amount every time the blank is 40 released from the automatic clamp, the shaft is connected to a cylindrical shaft 74 journaled in suitable spaced pedestals 76 mounted on a support 45 77. Keyed on shaft 74 between the pedestals is a ratchet 78 (Fig. 6) which is turned by a pawl 79 mounted in a suitable clutch, such as a housing 81 surrounding the ratchet and having a radial arm 82 provided with holes 83. Pivoted 50 suspended from any desired hole in this arm is a link 84 pivotally connected at its lower end to one end of a substantially horizontal beam 86 adapted to rock vertically on its opposite end.

In order to oscillate housing 81, beam 86 is 55 rocked by a cam 87 fixed on a shaft 88 journaled in pedestal bearings 89 on support 77. As the cam is rotated by a chain and sprocket drive 91 from shaft 64, it engages a roller 92 journaled in beam 86, the roller being held in contact with the cam at all times by a coil spring 93 compressed between the beam and the bottom of a well 94 in the support. To prevent the mechanism from being jammed in case the automatic clamp is accidentally delayed in releasing the blank for feeding and turning, the beam is pivoted on a plunger 96 disposed in a bore 97 in the support and normally spaced from the bottom of the bore by a coil spring 98. As spring 98 is stronger than spring 93, it is not compressed in normal operation, but if the blank refuses to turn, the end of the beam connected to the plunger compresses the spring under it and that end of the beam oscillates instead of the other end.

To make it unnecessary to provide a hardened 75

and tempered mandrel as long as the tube to be formed, mandrel 24 is made in two parts with its relatively short and hardened front part projecting but a relatively short distance through the roll pass. This mandrel is connected at its rear end to a cylinder 99 by which it is pulled back through the blank after its hardened portion has progressed a suitable distance through the mill with the blank. The rolls cause the blank to 10 tightly grip the mandrel, so that after the spindle chuck reaches the automatic clamp and can go no farther the chuck can be released, the carriage backed up and the chuck then caused to grip the mandrel itself. Subsequent advancement of the mandrel carries the blank along with it even though not gripped by the chuck.

To summarize the operation of the tube reducing apparatus described above, a tubular blank 26 is mounted on mandrel 24 and is clamped to carriage 51 by chuck 54. The front end of the blank encircles the tapered end of the mandrel and is disposed in the pass of reducing rolls 14 when the track housing is at the rear end of the bed plate 3. With the blank held in fixed position by clamp 69, disc 3 is rotated whereby the track housing is moved forward and rolls 14 taper the end of the blank before running off the end of it. During the return stroke of the mill clamp 69 releases the blank which is fed forward 30 an increment by carriage 51 that is pushed ahead by cylinder 56 until it strikes constantly moving stop 58 on screw 60. At this time the blank is again clamped in place by clamp 69 and the horizontal rolls taper an unreduced increment 35 and further reduce the tapered end of the blank. However, during the first few cycles of operation of the mill the front end of the blank is sunk upon the tapered front end of the mandrel instead of having its wall thickness reduced, whereby 40 by the end of the tube is upset to maintain a thick wall that prevents splitting open.

This tapering alone continues until a sufficient length of the blank extends through the rear roll pass to be engaged by rolls 14 throughout the 45 working stroke, whereupon the foremost portion of the blank is engaged by the rolls while they are moving parallel to its axis and a tube of uniform wall thickness is produced, with the exception of the upset end. By this time the blank 50 on the exit side of the rear roll pass is also long enough to extend into the front pass where it is smoothed and shaped by finishing rolls 18. The mandrel and blank continue to be fed ahead step by step, and between each step a portion of the 55 blank is reduced by the mill rolls. During each feeding step the blank is also turned a predetermined number of degrees by spindle 53 through which it extends. At intervals the mandrel is pulled back through the blank by cylinder 60 99 which also serves to strip the mandrel from the finished tube.

This invention is particularly applicable to the cold rolling of tubes, and some of the advantages mentioned, such as improvement of the grain 65 structure of the blank and substantially unlimited reduction in one pass through the mill, refer to cold rolling. Nevertheless, it will be understood that the invention can likewise be practiced to advantage in the hot rolling of 70 tubular blanks.

Although the invention has been described as contemplating holding the blank stationary while the mill is reciprocated to reduce it, it will be understood that the mill can be stationary and 75 the blank reciprocated in it as it is fed through

the mill. Also, if desired, the blank-turning mechanism can be omitted if three pairs of rolls are used in the mill. In such a case the grooves in the rear and center rolls are preferably semi-cylindrical in cross section, while those in the front pair have flat outwardly flaring side walls. The front rolls smooth out the marks left from the previous pass and loosen the tube from the mandrel. 5

In the modification shown in Figs. 8, 9 and 10 10 the roll-engaging areas of the track plates 101 are similar to track plates 7 of Fig. 2, and there is only one roll housing 102 and one pair of rolls 103 disposed in the track housing 104. The shape of the grooves 105 in this single pair of rolls is 15 relied upon to reduce and shape the blank into a cylindrical tube. Accordingly, as best shown in Figs. 9 and 10, each roll groove 105 is of the tapering type, that is, it is semi-cylindrical in cross section and gradually decreases in width 20 and depth as the roll is encircled, the smaller end of the groove being of uniform size for a short distance so that it will not taper the smaller end portion of each increment of the tubular blank rolled. Consequently, each time crank 106 25 moves the track housing from its left hand position on bed plate 107, as viewed in Fig. 8, to the position shown, the track plates cause the rolls to roll forwardly, and inwardly for part of the distance, along a portion of the blank 110. 30

In the starting position of the rolls the deep ends of their grooves are opposite each other for receiving an unreduced increment of the blank, but as they roll toward the front end of the blank the surfaces of the two grooves gradually approach 35 each other and reduce the increment of the blank to tapered form. Near the end of the working stroke the groove surfaces cease to approach each other and a cylindrical increment of a tube is thereby produced. During each working 40 stroke this operation is repeated until the entire blank has been fed between the rolls and has been reduced to a tube. The shape of the tracks and roll grooves thus effect sinking of the blank in two different ways; that is, as the rolls move bodily 45 toward each other their grooves become shallower.

To keep like areas of grooves 105 opposite each other at all times, the roll necks are provided with sprockets 108 that mesh with chains 109 anchored at their ends. Preferably, the rear ends of the 50 chains are connected to any suitable rigid support 111 at the rear of the bed plate, while their front ends are connected to rods 112 slidably mounted in plates 113 affixed to the rear of the track housing. The rods are biased rearwardly by coil 55 springs 114 which permit the chains to move away from plates 113 far enough to compensate for the change in effective diameter of the rolls as different points in the roll grooves come into contact with the blank. 60

According to the provisions of the patent statutes, I have explained the principle and mode of operation of my invention and have illustrated and described what I now consider to represent its best embodiment. However, I desire to have it 65 understood that, within the scope of the appended claims, the invention may be practiced otherwise than as specifically illustrated and described.

I claim:

1. A tube rolling mill comprising a track housing 70 open from end to end and provided interiorly with a pair of spaced track surfaces having substantially parallel areas merging into areas inclined away from each other toward the exit end of the housing, a roll housing disposed in said 75

- track housing between said tracks, a pair of grooved rolls rotatably mounted in said roll housing, a mandrel extending through the roll pass formed by the roll grooves and adapted to support 5 a tubular blank, means for effecting relative longitudinal reciprocable movement between said track housing and blank to cause said rolls to periodically roll simultaneously on the blank toward the entering end of the blank and toward each other to elongate a portion of the blank, the 10 rotation of the rolls being controlled principally by their frictional engagement with the tracks and blank, means for holding said track housing and the unrolled portion of the blank against movement in the same direction during the blank-reducing steps, and means for periodically subjecting successive unrolled increments of said blank to the action of said rolls whereby to periodically roll successive portions of the blank. 15
- 20 2. A tube rolling mill comprising a track housing open from end to end and provided interiorly with a pair of spaced track surfaces having substantially parallel areas merging into areas inclined away from each other toward the exit end of the housing, a roll housing disposed in said track housing between said tracks, a pair of grooved rolls rotatably mounted in said roll housing in frictional engagement with said tracks, a mandrel extending through the roll pass formed 25 by the roll grooves and adapted to support a tubular blank, means for reciprocating said track housing longitudinally of the mandrel to cause said rolls to periodically roll simultaneously on the blank toward the entering end of the blank and toward each other to elongate a portion of the blank, said rolling movement of the rolls being caused solely by their frictional engagement with said tracks and blank, means for holding the unrolled portion of the blank in fixed position during 30 each blank-reducing step, and means for periodically advancing successive unrolled increments of said blank into the roll pass whereby to periodically roll successive portions of the blank.
- 35 3. A tube rolling mill comprising a track housing open from end to end and provided interiorly with a pair of spaced track surfaces having substantially parallel areas merging into areas inclined away from each other toward the front of the housing, a roll housing disposed in said track housing between said tracks, a pair of grooved rolls rotatably mounted in said roll housing in frictional engagement with said tracks, a mandrel extending through the roll pass formed by the roll grooves and adapted to support a tubular blank, means for effecting relative reciprocable movement 40 between said track housing and blank to cause said rolls to periodically roll simultaneously toward the front end of the blank and toward each other to elongate a portion of the blank, and means for periodically subjecting successive unrolled increments of said blank to the action of said rolls, said inclined areas of the tracks being formed to cause the rolls to approach each other gradually during the first part of their working stroke followed by a relatively rapid approach and then by a gradual approach just before the rolls start to move parallel to the axis of the blank. 45
- 45 4. A tube rolling mill comprising a track housing open from end to end and provided interiorly with a pair of spaced track surfaces having substantially parallel areas merging into areas inclined away from each other toward the exit end of the housing, said housing being provided with a second pair of spaced track surfaces at right angles to said first pair and likewise having substantially parallel areas merging into areas inclined away from each other toward the exit end of the housing, a roll housing disposed in said track housing between each pair of tracks, a pair of grooved rolls rotatably mounted in each roll housing in frictional engagement with the adjoining pair of tracks, the grooves in the rolls between said first-mentioned tracks having outwardly flaring flat side walls, and the grooves in the other pair of rolls being substantially semi-circular in cross section, a mandrel extending through the 50
- 55 angles to said first pair and likewise having substantially parallel areas merging into areas inclined away from each other toward the exit end of the housing, a roll housing disposed in said track housing between each pair of tracks, a pair of grooved rolls rotatably mounted in each roll housing in frictional engagement with the adjoining pair of tracks, a mandrel extending through the roll pass formed by the roll grooves and adapted to support a tubular blank, means for effecting relative reciprocable movement between said track housing and blank to cause each pair of rolls to roll simultaneously on the blank toward the entering end of the blank and toward each other to elongate a portion of the blank, the rotation of the rolls being controlled principally by their frictional engagement with the tracks and blank, means for holding said track housing and the unrolled portion of the blank against movement in the same direction during the blank-reducing steps, and means for periodically subjecting successive unrolled increments of said blank to the action of said rolls whereby to periodically roll successive portions of the blank. 55
- 60 5. A tube rolling mill comprising a track housing open from end to end and provided interiorly with a pair of spaced track surfaces having substantially parallel areas merging into areas inclined away from each other toward the exit end of the housing, said housing being provided with a second pair of spaced track surfaces at right angles to said first pair and likewise having substantially parallel areas merging into areas inclined away from each other toward the exit end of the housing, a roll housing disposed in said track housing between each pair of tracks, a pair of grooved rolls rotatably mounted in each roll housing in frictional engagement with the adjoining pair of tracks, a mandrel extending through the roll pass formed by the roll grooves and adapted to support a tubular blank, means for effecting relative reciprocable movement between said track housing and blank to cause each pair of rolls to roll simultaneously on the blank toward the entering end of the blank and toward each other to elongate a portion of the blank, the rotation of the rolls being controlled principally by their frictional engagement with the tracks and blank, means for holding said track housing and the unrolled portion of the blank against movement in the same direction during the blank-reducing steps, means for periodically subjecting successive unrolled increments of said blank to the action of said rolls, and means for turning the blank on its axis between working strokes. 65
- 65 6. A tube rolling mill comprising a track housing open from end to end and provided interiorly with a pair of spaced track surfaces having substantially parallel areas merging into areas inclined away from each other toward the front of the housing, said housing being provided with a second pair of spaced track surfaces at right angles to said first pair and likewise having substantially parallel areas merging into areas inclined away from each other toward the front of the housing, a roll housing disposed in said track housing between each pair of tracks, a pair of grooved rolls rotatably mounted in each roll housing in frictional engagement with the adjoining pair of tracks, the grooves in the rolls between said first-mentioned tracks having outwardly flaring flat side walls, and the grooves in the other pair of rolls being substantially semi-circular in cross section, a mandrel extending through the 70
- 75

- roll pass formed by the roll grooves and adapted to support a tubular blank, means for effecting relative reciprocable movement between said track housing and blank to cause each pair of rolls to roll simultaneously toward the front end of the blank and toward each other to elongate a portion of the blank, means for periodically subjecting successive unrolled increments of said blank to the action of said rolls, and means for periodically turning the blank on its axis.
7. A tube rolling mill comprising a track housing open from end to end and provided interiorly with a pair of spaced track surfaces having substantially parallel areas merging into areas inclined away from each other toward the front of the housing, a roll housing disposed in said track housing between said tracks, a pair of grooved rolls rotatably mounted in said roll housing in frictional engagement with said tracks, a mandrel extending through the roll pass formed by the roll grooves and adapted to support a tubular blank, means for reciprocating said track housing to cause said rolls to periodically roll simultaneously toward the front end of the blank and toward each other to elongate a portion of the blank, means for returning said rolls to their starting position after each working stroke, means for delaying said return of the rolls during the return stroke of said track housing, and means for periodically advancing successive unrolled increments of said blank into the roll pass.
8. A tube rolling mill comprising a track housing open from end to end and provided interiorly with a pair of spaced track surfaces having substantially parallel areas merging into areas inclined away from each other toward the front of the housing, a roll housing disposed in said track housing between said tracks, a pair of grooved rolls rotatably mounted in said roll housing in frictional engagement with said tracks, a mandrel extending through the roll pass formed by the roll grooves and adapted to support a tubular blank, means for reciprocating said track housing longitudinally of the mandrel to cause said rolls to periodically roll simultaneously toward the front end of the blank and toward each other to elongate a portion of the blank, means associated with said track housing for engaging said roll housing to return it to starting position after each working stroke, fluid pressure means for delaying the return of said roll housing during the return stroke of said track housing, and means for periodically advancing successive unrolled increments of said blank into the roll pass.
9. A tube rolling mill comprising a track housing open from end to end and provided interiorly with a pair of spaced track surfaces having substantially parallel areas merging into areas inclined away from each other toward the front of the housing, a roll housing disposed in said track housing between said tracks, a pair of grooved rolls rotatably mounted in said roll housing in frictional engagement with said tracks, a mandrel extending through the roll pass formed by the roll grooves and adapted to support a tubular blank, means for reciprocating said track housing longitudinally to cause said rolls to periodically roll simultaneously toward the front end of the blank and toward each other to elongate a portion of the blank, means constantly urging said blank forward, means periodically arresting said forward movement, and means for clamping said blank in fixed position when its forward movement is arrested.
10. A tube rolling mill comprising a track hous-
- ing open from end to end and provided interiorly with a pair of spaced track surfaces having substantially parallel areas merging into areas inclined away from each other toward the front of the housing, a roll housing disposed in said track housing between said tracks, a pair of grooved rolls rotatably mounted in said roll housing in frictional engagement with said tracks, a mandrel extending through the roll pass formed by the roll grooves and adapted to support a tubular blank, means for reciprocating said track housing longitudinally to cause said rolls to periodically roll simultaneously toward the front end of the blank and toward each other to elongate a portion of the blank, means constantly urging said blank forward, means periodically arresting said forward movement, means for clamping said blank in fixed position when its forward movement is arrested, and means for periodically drawing said mandrel backwardly in said blank.
11. A tube rolling mill comprising a track housing open from end to end and provided interiorly with a pair of spaced track surfaces having substantially parallel areas merging into areas inclined away from each other toward the front of the housing, a roll housing disposed in said track housing between said tracks, a pair of grooved rolls rotatably mounted in said roll housing in frictional engagement with said tracks, a mandrel extending through the roll pass formed by the roll grooves and adapted to support a tubular blank, means for reciprocating said track housing longitudinally to cause said rolls to periodically roll simultaneously toward the front end of the blank and toward each other to elongate a portion of the blank, means constantly urging said blank forward, means periodically arresting said forward movement, means for clamping said blank in fixed position when its forward movement is arrested, and means for turning said blank on its axis while it is moving forward.
12. Feeding and turning apparatus for use with a tube rolling mill, comprising a carriage, means biasing the carriage toward said mill, a hollow spindle journaled in the carriage for receiving a mandrel supporting a tubular blank, means for detachably clamping the mandrel and blank in said spindle, means for periodically clamping the mandrel and blank in fixed position relative to the mill, and means for rotating said spindle a predetermined amount while the carriage is moving forward.
13. Feeding and turning apparatus for use with a tube rolling mill, comprising a carriage, means biasing the carriage toward said mill, a constantly rotating screw, a stop threaded on said screw and projecting into the path of the carriage, a hollow spindle journaled in the carriage for receiving a mandrel supporting a tubular blank, means for detachably clamping the mandrel and blank in said spindle, means for periodically clamping the mandrel and blank in fixed position relative to the mill, a rotatable shaft operably connected to said spindle for turning it, a pawl and ratchet members for turning said shaft, a beam operably connected at one end to one of said members for actuating it, resilient means pivotally supporting the opposite end of the beam, and means normally oscillating said first-mentioned end of the beam.
14. A tube rolling mill comprising a track housing open from end to end and provided interiorly with a pair of spaced track surfaces having substantially parallel areas, a roll housing disposed in said track housing between said tracks, a pair

- of grooved rolls rotatably mounted in said roll housing in frictional engagement with said tracks, the grooves in each roll being substantially semi-cylindrical in cross section and tapering from a wide and deep portion to a relatively narrow and shallow portion, a mandrel extending through the roll pass formed by the roll groove and adapted to support a tubular blank, means for effecting relative reciprocable movement between said track housing and blank, the axes of the rolls being free to accommodate themselves to the relative speeds of the tracks and blank and means for maintaining like areas of said grooves opposite to each other at all times. 5
15. A tube rolling mill comprising a track housing open from end to end and provided interiorly with a pair of spaced track surfaces having substantially parallel areas, a roll housing disposed in said track housing between said tracks, a pair of grooved rolls rotatably mounted in said roll housing in frictional engagement with said tracks, the grooves in each roll being substantially semi-cylindrical in cross section and tapering from a wide and deep portion to a relatively narrow and shallow portion, a mandrel extending through the roll pass formed by the roll groove and adapted to support a tubular blank, means for effecting relative reciprocable movement between said track housing and blank, the axes of the rolls 10
- 10 being free to accommodate themselves to the relative speeds of the tracks and blank and means for maintaining like areas of said grooves opposite to each other at all times. 15
15. A tube rolling mill comprising a track housing open from end to end and provided interiorly with a pair of spaced track surfaces having substantially parallel areas, a roll housing disposed in said track housing between said tracks, a pair of grooved rolls rotatably mounted in said roll housing in frictional engagement with said tracks, the grooves in each roll being substantially semi-cylindrical in cross section and tapering from a wide and deep portion to a relatively narrow and shallow portion, a mandrel extending through the roll pass formed by the roll groove and adapted to support a tubular blank, means for effecting relative reciprocable movement between said track housing and blank, the axes of the rolls 20
- 20 being free to accommodate themselves to the relative speeds of the tracks and blank and means for maintaining like areas of said grooves opposite to each other at all times. 25
25. A tube rolling mill comprising a track housing open from end to end and provided interiorly with a pair of spaced track surfaces having substantially parallel areas, a roll housing disposed in said track housing between said tracks, a pair of grooved rolls rotatably mounted in said roll housing in frictional engagement with said tracks, the grooves in each roll being substantially semi-cylindrical in cross section and tapering from a wide and deep portion to a relatively narrow and shallow portion, a mandrel extending through the roll pass formed by the roll groove and adapted to support a tubular blank, means for effecting relative reciprocable movement between said track housing and blank, the axes of the rolls 20
- 20 being free to accommodate themselves to the relative speeds of the tracks and blank and means for maintaining like areas of said grooves opposite to each other at all times. 25

being free to accommodate themselves to the relative speeds of the tracks and blank sprockets mounted on the ends of said rolls, and means anchored at the rear of said track housing and meshing with said sprockets, the front ends of 5 said means also being anchored.

16. A tube rolling mill comprising a housing open from end to end and provided interiorly with a pair of spaced track surfaces having substantially parallel areas merging into areas inclined away from each other toward the exit end of the housing, a pair of grooved rolls rotatably mounted between said track surfaces in frictional engagement therewith, a mandrel extending through the roll grooves and adapted to support a tubular blank, means for effecting relative longitudinal reciprocable movement between said housing and blank to cause said rolls to periodically roll simultaneously on the blank toward its entering end and toward each other to reduce 15 and elongate a portion of the blank, the axes of the rolls being free to accommodate themselves to the relative speed of the tracks and blank, and means for periodically subjecting successive unrolled increments of said blank to the action of 20 said rolls whereby to periodically roll successive portions of the blank. 25
